J. A. DONNELLY,
AIR REMOVAL FOR RADIATORS,
APPLICATION FILED MAY 12, 1906.

1,181,439.

Patented May 2, 1916.

UNITED STATES PATENT OFFICE.

JAMES A. DONNELLY, OF BROOKLYN, NEW YORK.

AIR REMOVAL FOR RADIATORS.

1,181,439.

Specification of Letters Patent.

Patented May 2, 1916.

Application filed May 12, 1906. Serial No. 316,426.

To all whom it may concern:

Be it known that I, JAMES A. DONNELLY, a citizen of the United States, and a resident of Brooklyn, in the county of Kings and State of New York, have invented certain new and useful Improvements in Air Removal for Radiators, of which the following is a specification.

This invention appertains to certain novel and useful improvements in circulating systems and has particular application to improved means and methods of removing air from heating systems.

It consists in the construction, combination and arrangement of parts set forth in and falling within scope of the appended claims.

In the accompanying drawings like characters of reference indicate like parts in all the views and, Figure 1, shows my improvements applied and employed in connection with a radiator heating system. Fig. 2, is a detail sectional view of the restriction valve employed at the outlet of each radiator. Fig. 3, is a detail view of the controlling diaphragm valve employed in my system.

Heretofore, in automatically removing air from radiators, especially those installed in residences and small dwellings, it has been customary to place an air valve on the radiator, which is controlled by the difference in temperature between steam and air. In my present invention I propose to remove the air by pressure alone, irrespective of temperature.

Referring to the drawings in detail, wherein is shown by way of illustration, a preferred embodiment of my invention, A indicates a steam heating boiler of a well-known type, while B B designate radiators.

At 5 is a steam supply main leading from the boiler and communicating with each of the radiators by branches 6 each branch having a valve 7, to control the admission of steam to the radiator. A continuation 5^a, of the steam main has leading from it a branch pipe 8, which connects with the underside of the diaphragm or controlling valve indicated as a whole by C. Leading from the radiators are branch returns 9, communicating with the main return 10, leading back toward the boiler. Each of the branch returns is provided with a restricting valve D, shown in detail in Fig. 2. The main return at a point near the

valve C, is divided into two branches, one shown at 11, leading to the boiler to convey the water of condensation, the other branch 12, leading from the main to the upper portion of the diaphragm valve C; and is designed to convey air to said valve. The pipe 12 is shown as including a vertical portion arranged above the return pipe 10, whereby the water in the return is prevented from passing to the valve C. By this means the air and water in the return are separated.

13 is a pipe for discharging air from the diaphragm valve to any suitable point of discharge, in the present instance the ash pit of the furnace. A check valve 14, is located in the air discharge line 13, to prevent the return of the air.

The valve C, shown in detail in Fig. 3, is provided with a high pressure chamber 15, into which leads the steam pipe 8, and a low pressure chamber 16, communicating with the inlet from the return 12, and the return discharge 13. These chambers are separated by the diaphragm 17, connected with the vertical valve stem 18, carrying a valve 19, controlling the return passage through the valve. This stem 18, projects through the high pressure chamber and through stuffing box 20, outside thereof and is connected with the lever 21, carrying the adjustable weight 22.

23 is a link connecting the lever with the casing of the diaphragm.

I will now proceed to describe the mechanical constructions of the restriction valve D at the outlet of the radiator in the present instance.

The valve comprises an outer casing 24, an inner casing 25, within which is the restriction valve member 26, hinged or otherwise suspended at 27 to the top wall of the casing. The orifice 28 in the casing 25, forms a valve opening or seat controlled by the cone like portion 29, of the valve piece 26. At the relatively widened base portion of the cone, I form a grooved impact surface 30. Each of the valve pieces 26, may be weighted as at 31, and it is to be understood that each valve piece is weighted to suit the particular needs of its particular outlet.

The above briefly describes the mechanisms and elements I employ.

The operation of the system is briefly as follows:—Steam being up in the boiler, the valves 7 of the radiators are opened and the steam passes through the mains 5 and

branches 6 into the radiators. The diaphragm valve is normally held closed by the steam pressure on the underside of the diaphragm and can only be opened when the 5 pressure in the return and on top of the diaphragm plus the weight 22 exceeds such closing steam pressure. When steam is admitted to the radiators it acts to force the air through the restriction valve D, the pressure 10 of steam, air and water forcing such valve open. The air driven by the steam passing down the returns 9, 10, and 12, exerts pressure upon the diaphragm, and as such pressure plus the weight exceeds the steam pressure 15 upon the underside of the diaphragm, the valve 19, is moved away from its seat and the air escapes through such valve to the air discharge 13. The water of condensation meanwhile flowing down the return pipe 11. As the air flows from the radiator through the returns just described, the steam following naturally flows into the returns between the valves D and C and as such steam condenses in these returns the 20 pressure therein naturally drops until by the time all the air has passed through the valve C the pressure in the returns between the restriction valve D and the diaphragm C is so low that it, plus the weight is not sufficient 25 to hold the valve C open against the action of steam on the underside of the diaphragm and the valve 19 closes, all the air having 30 been driven out of the radiators and returns.

35 A further advantageous feature incident to my construction is this:—After the system has been heated up, if sections of the radiators are closed up and become cold and filled with air, the opening of the inlet valve 10 7 of one of these cold radiators compresses the air therein and forces it out through the restricting valve into the return space before occupied by steam. This raises the pressure in the returns and serves to open the control 45 valve C and maintain it in a more or less open position until the air in the return passes through the valve C and is discharged.

The valve piece 26 of the restriction valve 50 D is weighted sufficiently to maintain the pressure in the return at a point below that in the supply. For instance, if the pressure in the supply is two pounds, the valve piece 26 would be weighted in such proportion to 55 the area of the valve seat as to maintain the pressure in the return at one and three-quarter pounds. It is of course, desirable that the area of the restricted opening 28 be less than the area of the pipes so that the flow in 60 the return pipes will not be affected sufficiently to materially change the pressure in the returns.

In order that the pressure in the return main may be properly maintained relative to 65 the supply the usual drips from the steam

to the return main are provided with a loop seal or equivalent device such as shown at 32.

After steam has been raised in the boiler and the radiators heated, and all air expelled through the valve C and past the 70 check valve 14, the steam will continue to circulate below atmospheric pressure as the fire cools, and the check valve 14 or other similar device automatically serving to prevent the return of air.

75

In the accompanying drawings I have shown my invention embodied in forms at present preferred by me; but it will be understood that various modifications and changes may be made without departing 80 from the spirit of my invention and without exceeding the scope of the claims.

What I claim is:

1. In a steam circulating system, the combination of a steam generator, a radiator, a supply pipe and a return pipe connecting the radiator with the generator, a pressure-operated restriction valve in the return pipe to maintain the pressure in the return pipe a predetermined amount below that of the supply, said return pipe having an air outlet to the atmosphere between the radiator and the generator, and a pressure-operated valve for controlling said air outlet in the return pipe and arranged to open said outlet 90 when the pressure in the return pipe reaches a predetermined amount.

95

2. In a steam circulating system, the combination of a steam generator, a radiator, a supply pipe and a return pipe connecting the radiator with the generator, said return pipe having an air outlet to the atmosphere from the return pipe, a pressure operated restriction valve in the return to maintain the pressure in the return pipe a predetermined amount below that of the supply, and a pressure operated valve for controlling said air outlet and arranged to be operated when the pressure in the return pipe reaches a predetermined amount.

100

3. In a steam circulating system, the combination of a source of steam supply, a radiator, a supply pipe and a return pipe connecting the radiator with the source of steam supply, said return pipe having an air outlet to the atmosphere, a pressure operated valve in the return pipe acting to automatically maintain the pressure in the return pipe below that in the supply pipe, and a pressure operated valve controlling said air outlet 115 and arranged to open said outlet when the pressure in the return pipe reaches a predetermined amount.

110

4. In a steam circulating system, the combination of a source of steam supply, a radiator, a supply pipe and a return pipe connecting the radiator with the source of steam supply, said return pipe having an air outlet to the atmosphere, a pressure operated valve in the return pipe acting to automati- 120

125

130

5. In a steam circulating system, the combination of a source of steam supply, a radiator, a supply pipe and a return pipe connecting the radiator with the source of steam supply, said return pipe having an outlet to the atmosphere, a pressure operated valve in the return pipe acting to automatically maintain a predetermined differential of pressure between the said supply and return pipes, and means controlling said outlet and operated by the differential of pressure in the supply and return pipes.
6. In a steam circulating system, the combination of a steam generator, a radiator, a supply pipe and a return pipe connecting the radiator with the generator, an automatic pressure operated valve in the return pipe for causing a predetermined differential of pressures in the return pipe and the supply pipe, said return pipe having an air outlet to the atmosphere in the return pipe between said valve and the generator, a valve controlling said outlet, a diaphragm operatively connected with said valve, means forming with said diaphragm a pressure chamber on each side thereof, means for withdrawing the valve from its seat, one of said chambers communicating with the supply pipe to overcome said means and seat the valve, and the other chamber communicating with the return pipe, the arrangement being such that the combined pressure of steam and air in the return pipe together with said means operates to open the valve against supply pressure to permit escape of air from the return pipe through said outlet to the atmosphere.
7. In a steam circulating system, the combination of a steam generator, a radiator, a supply pipe and a return pipe connecting the radiator with the generator, an automatic pressure operated valve in the return pipe for causing a predetermined differential of pressures in the return pipe and the supply pipe, said return pipe having an air outlet in the return pipe between said valve and the generator, a valve controlling the outlet, a diaphragm operatively connected with said valve, means forming with said diaphragm a pressure chamber on each side of the diaphragm, means for withdrawing the valve from its seat, one of said chambers communicating with the supply pipe to overcome said means and seat the valve, the other chamber communicating with the return pipe, said last named communication being provided with means for preventing water of condensation entering said other
- chamber from the return pipe, the arrangement being such that the combined pressure of steam and air in the return pipe together with said means operates to open the valve against supply pressure to permit escape of air through said outlet.
8. In a steam circulating system, the combination of a steam generator, a radiator, a supply pipe and a return pipe connecting the radiator with the generator, an automatic pressure operated valve in the return pipe for causing a predetermined differential of pressures in the return pipe and the supply pipe, said return pipe having an air outlet in the return pipe between said valve and the generator, a valve controlling the outlet, a diaphragm operatively connected with said valve, means forming with said diaphragm a pressure chamber on each side of the diaphragm, means for withdrawing the valve from its seat, one of said chambers communicating with the supply pipe to overcome said means and seat the valve, the other chamber communicating with the return pipe, said last named communication being provided with means for separating the air and water of condensation in the return pipe, the arrangement being such that the combined pressure of steam and air in the return pipe together with said means operates to open the valve against supply pressure to permit escape of air through said outlet.
9. In a steam circulating system, the combination of a steam generator, a radiator, a supply pipe and a return pipe connecting the radiator with the generator, an automatic pressure operated valve in the return pipe for causing a predetermined differential of pressures in the return pipe and the supply pipe, the return pipe having an air outlet to the atmosphere between said valve and the generator, a valve controlling said outlet, a diaphragm operatively connected with said valve, means forming with said diaphragm a pressure chamber on each side of the diaphragm, means for withdrawing the valve from its seat, one of said chambers communicating with the supply pipe to overcome said means and seat the valve, a pipe connecting the other chamber communicating with the return pipe, said pipe connecting said other chamber and the return pipe having a part extending vertically above the return pipe, the arrangement being such that the combined pressure of steam and air in the return pipe, together with said means, operates to open the valve against supply pressure to permit escape of air through said outlet, and the water of condensation passes to the generator independently of said valve.
10. In a steam heating apparatus, the combination of a steam boiler, a radiator, a supply pipe and a return pipe connecting said boiler and radiator and forming there-

with a circulating system, the return portion of said system having an outlet above the normal water level therein, and a pressure actuated valve device for controlling said outlet, said pressure actuated valve device being in communication with the system above the normal water level therein, arranged to be acted upon differentially by the pressures in the supply and return portions of the system, and adapted to close said outlet when a predetermined difference in pressure between the supply and return portions of the system is exceeded.

11. In a steam heating apparatus, the combination of a steam boiler, a radiator, a supply pipe and a return pipe connecting said boiler and radiator and forming therewith

a circulating system, the return portion of said system having an outlet above the normal water level therein, means for restricting the flow of fluid from the radiator to the return pipe whereby a given differential of pressure may be maintained between the radiator and the return pipe, and means for maintaining said differential of pressure, 25 said means comprising a pressure actuated valve device for controlling said outlet arranged to be operated by the variation of pressures in the supply and return portions of the system.
